PRESSURE RIBBON-TYPE GAS BURNER

Louis D. Houlls, Cincinnati, Ohio

Application July 31, 1944, Serial No. 547,320

7 Claims. (Cl. 158—114)

1

This invention relates to gas burners and it has reference more particularly to improvements in gas burners of a type especially adapted for industrial installations for use in heating and ventilating equipment, in food processing apparatus, bakers' ovens, stoves and ranges, and in other installations where a uniform and steady flame is desired.

It is one of the principal objects of this invention to provide a gas burner, of the character above stated, of a simplified construction; that is easy to install in any of its various applications; that is readily adjustable for determination of flame character and which is easy to disassemble to facilitate cleaning, repair or overhaul of its parts.

It is also an object of this invention to provide a gas burner having the advantages above stated, that will burn with a uniform, ribbon-like flame, and which, by reason of its arrangement of parts and their details of construction, has great tolerance of turn-down without causing backfiring and has great tolerance of primary air and flame increase without causing the flame to lift or to blow out.

Another object of this invention is to provide a gas burner that is suitable for use of primary air at atmospheric pressure and which can be successfully combined with a blower to furnish both primary and secondary air under pressure and thereby adapted for use in normally closed places not equipped for admission of secondary air.

Yet another object of the invention is to provide a gas burner of the atmospheric Venturi type that, without structural changes or modifications, can be combined with means for supplying air under pressure, and thus converted to a pressure air or pressure air and gas burner.

More specifically stated, the objects of this invention reside in the provision of a gas burner for both high and low burning flame; that can use air at atmospheric pressure when a minimum or low burning flame is required and/or as a pre-mixed, or induced air pressure burner, when maximum or high flame is required. Furthermore, to provide such a burner with novel means for its automatic control.

Still further objects of the invention reside in the details of construction and combination of parts as employed in the burner in the various modifications thereof and either as an atmospheric air or as a pressure burner.

In accomplishing the above mentioned and other objects of the invention, I have provided

2

the improved details of construction, the preferred forms of which are illustrated in the accompanying drawings, wherein—

Fig. 1 is a longitudinal section of a gas burner which is typical of those embodied by this invention, showing one form of construction suitable for use of air at atmospheric pressure.

Fig. 2 is a top, or plan view of the same burner with parts thereof broken away for purposes of explanation and better illustration.

Fig. 3 is a cross section taken on the line 3—3, in Fig. 1.

Fig. 4 is a detail showing, in cross section and in perspective, a burner of a simplified alternative form.

Fig. 5 is a similar cross-sectional view of a burner of another alternative form of construction.

Fig. 6 is a side view of a burner typical of the present type that is equipped to use primary air either at atmospheric pressure or under forced pressure.

Fig. 7 is a top view of the burner shown in Fig. 6.

Fig. 8 is an enlarged, cross-sectional view of the delayed action gas control valve used in the pressure system of Fig. 6.

Fig. 9 is a burner arrangement equipped with means for supplying it with primary and secondary air under pressure.

Fig. 10 is a cross-sectional view and perspective on the line 10—10 in Fig. 9.

Fig. 11 is a cross-sectional view of an oven in which a burner embodying improvements of the present invention is installed.

Fig. 12 is a horizontal section, taken on the line 12—12 in Fig. 11.

Referring more in detail to the drawings—

As was previously stated, the present burner is adaptable to various uses and the novel features of construction may be embodied in such burners of different detail. For example, the burner may be designed for using primary air supplied thereto at atmospheric pressure, or primary air under pressure, or it may be designed to receive additional primary and secondary air under forced delivery as supplied by a blower. Furthermore, the burner might be operated under control of automatic control means. In the following specification, I will first describe the burner in a form of construction utilizing primary air supplied under control at atmospheric pressure, and will later describe the burner as equipped for the use of atmospheric air for low burning flame and air

under pressure for high burning flame, and also in connection with means for supplying it with both primary and secondary air under forced delivery and also to operate under automatic control.

First describing the burner as shown in Figs. 1, 2 and 3: 1 designates the burner tube within which a fuel mixture of air and gas is supplied to the burner outlets. This tube is shown as being a cylindrical iron pipe of substantial length, as may be determined by its particular use or by requirements in specific installations. The tube is not necessarily cylindrical, but may be square or of other cross sectional shape. It is closed at its outer end by a cap 2 threaded thereonto and at its inner end it is connected by means of a pipe fitting 3 with a short length of pipe 4 in which a Venturi sleeve 5 is fitted; the sleeve providing a Venturi passage 6 that is directed into the burner tube 1. The pipe 4 has threaded connection at its outer end with a T-fitting 7 through which the primary air and gas is supplied to the burner tube to form the fuel mixture and, as will presently be understood, the fuel mixture is delivered into tube 1 under sufficient pressure as to insure an even distribution and discharge along the full length of the tube.

The T-fitting 7 has an outer end opening 8, opposite that into which the pipe 4 is threaded, for admittance of atmospheric air to the burner under control of an adjustable closure cap 10. The cap 10 is supported by legs 11 cast therewith and extended inwardly from its inner face. These are connected to an externally threaded ring 12 that is threaded into the opening 8. By turning the cap 10, the ring will be advanced farther into or outwardly from the opening 8 and will thus adjust the cap accordingly to control the inflow of air to supply the burner according to the mixture and flame desired. The cap 10, as noted in Fig. 1, is formed with a central opening 13 so that all air to the burner cannot be shut off even though the cap be tightly closed against the fitting.

Gas under suitable pressure is supplied to the burner through a supply pipe 15 which threads into a housing 16. The housing 16, in turn, is threaded into the top opening of the T-fitting 7 and is held against unthreading by means of a set screw 17 tightened thereagainst.

The housing 16 is contained within the T-fitting 7 and within the housing 16 is a chamber 18 formed with a side opening 19 into which a small nipple 20 is threaded. The nipple has a tapered jet opening therethrough and this axially coincides with the axial line of the Venturi passage 6 and is directed through the latter into the burner tube. Threaded through the back wall of housing 16, opposite the jet opening 21 is a screw, or needle valve member, 23 having a conically tapered end portion 22 that by applying a screw driver through the opening 13 in cap 10, may be adjusted into and from the orifice 21 to regulate the rate of discharge of gas into the Venturi passage to supply the burner. The suction that is incident to this discharge of gas causes air to be drawn into the burner through the opening 8 as permitted by the adjustment of cap 10 and, as was previously mentioned, the gas jet causes the fuel mixture to enter the tube 1 under pressure sufficient to maintain an even distribution of the mixture to the burner outlets throughout the length of the tube.

Thus, it will be understood that with the gas

being supplied under a definite pressure and the needle valve adjusted to a setting for admittance of a desired flow of gas, the air cap 10 may be adjusted to admit air to produce a fuel mixture that will give the best or a desired character of flame.

The fuel mixture that is thus delivered into the tube 1 is discharged from the tube through a succession of small ports 25, formed in one or more rows extending lengthwise of the tube along its top side. These ports open from the tube into a closed duct 26 that is formed along the top of the tube. Preferably this duct is formed by applying an inverted channel iron member 27 along the top side of the pipe, then welding the edges of the channel flanges to the pipe walls along the lines of contact as shown at 28 in Fig. 3. The duct 26 is closed at its ends by walls 29, seen in Fig. 1.

Extending lengthwise of the top or horizontal wall of the channel member 27 as seen in Fig. 1, and formed in its top surface, is a channel 30. Drilled through the base of this channel at spaced intervals therealong, are ports 32 opening into the duct 26 for the outflow of the fuel mixture into the channel 30. Disposed upon the top wall of the channel member 27 and extending throughout its length is a transversely corrugated ribbon strip 35 of suitable sheet metal of the same width as the channel member 27, and providing a succession of cross channels 36 between its corrugations, all of which are in communication with the channel 30 and are open at their opposite ends to the opposite sides of the burner and flush with the side walls of the channel member 27. The ribbon strip 35 is overlaid, and is held in place thereon by a plurality of bolts 38 that are extended therethrough and through the member 27 and threaded into the top wall of the pipe 1, as is shown in Fig. 1.

With this arrangement of parts, the fuel mixture is supplied to the duct 26 from tube 1 through the ports 25, and from the duct 26 it passes through the ports 32 into the channel 30 and from this latter it is supplied to the succession of cross channels 36 of the corrugated ribbon strip and from them to the opposite sides of the burner. The arrangement of ducts, ports and channels, as described, provides a means that effectively counteracts or eliminates the tendency of backfiring regardless of how restricted the air supply may be and, furthermore, all tendency to blow out or to lift the flame under full supply of air and gas is overcome.

In Fig. 4, I have shown a modification of the invention which is a rather simplified type of burner, suitable for some installations. It is to be understood that this modified type would be equipped for attachment to air and gas supply means like or similar to that which has previously been described in connection with Fig. 1.

This simplified construction comprises a tubular manifold 1a which, like tube 1, is formed along its top side with two rows of fuel discharge ports 25', opening therefrom into a longitudinal duct 26' which, might be provided by applying an inverted channel member 27' longitudinally of and against the top side of the tube as was previously explained in connection with the description of tube 1, and securing this along its flange edges to the tube walls by welding as indicated at 28'. In the flat top wall of the channel member 27' is a centrally located and longitudinally extended row of spaced ports 32'. The fuel mixture supplied from the tube 1a to the duct 26' burns on

discharge from the latter through the ports 32'.

In Fig. 5, I have shown another modified or alternative form of burner tube or manifold. That, also, is applicable to air and gas supply means of that kind shown in Fig. 1. In this particular construction, an inverted channel iron member 27a is applied in direct contact along and against the top side of the tubular manifold 1a, with the top wall of the channel member engaging tightly against the tube wall instead of being spaced therefrom as in the burners of Figs. 3 and 4, and the flanges of this channel member are welded as at 28a to the sides of the tube wall.

A row of spaced ports 32x are directed downwardly through the central, contacting portions of the channel member 27a and tube wall into the tube. Overlying the member 27a, lengthwise thereof, is a plate 31x and formed therewith on its under side and along the longitudinal edges thereof are two transversely channeled ribs or flanges 40-40 and between the ribs is a longitudinal duct 41. The fuel mixture supplied by manifold 1a is admitted into this duct 41 through the ports 32x and is discharged laterally from the duct, in opposite directions, through the channels 42 formed in the ribs 40-40 and will burn in ribbon-like flames along the opposite sides of the burner tube.

The various modified forms of burner tubes are designed for use with the same fuel and air supply parts as shown in Fig. 1, and it is understood that the character of the flame may be changed or determined by the adjustment of the cap 10 and the needle valve 22.

Referring now to the adaptation of burners of these types to means for a forced delivery of primary air, or of forced delivery of primary and secondary air, and for automatic control as exemplified in the showing of Figs. 6 and 7 which illustrate a dual burner installation and assuming that any one of the previously described burner tube structures might be employed: Provision is made for supplying primary air at atmospheric pressure for low burning flame. Also there is provision for supplying primary air under pressure for high or maximum burning by a fan blower 50 of conventional design, arranged to be driven by an electric motor 51. The discharge neck 50' of the blower housing connects with a header 52 that is equipped at its opposite ends with tubular outlets 53 for supplying the two burners. Each outlet 53 is telescoped into a tubular neck 54 extended coaxially from the outer side of the air control cap 10 of one of the burners and is in open communication through the cap opening 13 with the fitting 7 with which the burner tube is connected as has been shown best in Fig. 6. Thus, through this connection, air under pressure from the blower will be delivered to the burner and a definite pressure can be maintained by adjustment of the cap 10 to a more or less open position over the opening 8, allowing escape of excess air.

With the arrangement of Fig. 6, gas is supplied from a source designated in Figs. 6 and 7 as a pipe 60 in which a shut off valve 61 is placed. The pipe 60 connects through a solenoid actuated valve 62, later to be described in detail, with a pipe 15' that connects through the top of the housing 16, previously described with chamber 18. Also, there is a by-pass pipe connection 65 between the supply pipe 60 and the pipe 15', in which connection a solenoid valve 66 is installed and leading from the pipe 65, between its connec-

tion with pipe 60 and the valve 66 is a small supply pipe 67 extended to a pilot burner 68 that is affixed to the burner manifold in position for igniting the fuel when it is discharged from the burner outlets. The solenoid valve 62 operates under control of a thermostat 69, diagrammatically shown in Figs. 6 and 11.

The wiring diagram that has been shown in connection with Fig. 6 indicates that electric current is supplied from lines 70 and 71 to a relay switch 72 from which circuit lines 73 and 74 lead to the solenoid valve 65 and other lines 75 and 76 lead from the wires 73 and 74, respectively, to the electric motor 51 which drives the blower 50. The thermostat 69 is connected in series in the circuit line 75 and it has circuit connections with the solenoid for actuating valve 62 in a manner whereby closing and opening of the circuit to the electric motor through the thermostatic means provided simultaneously energizes and deenergizes the solenoid valve to open or to close it. The relay switch 72 is under control of a conventional type of thermo-couple 77, located adjacent the pilot burner 68, connected to the switch 72 by means designated at 78. This thermo-couple is affected by heat from the pilot burner to so control the switch 72 as to cause it to maintain closed circuit connections with the lines 73 and 74 so long as the pilot is burning. Should the pilot light go out, then the valves 62 and 66 will both be deenergized and gas flow to the burner will be shut off. Gas may be manually cut off from the burner by closing valve 61.

Fig. 8 of the drawings shows the solenoid valve 62 to comprise a valve member 85 adapted to the valve passage 86 and connected to the lower end of the solenoid core 81. The solenoid coil 88, when energized, lifts the valve 85 and gas flows through passage 86 to the burner.

It is desirable to retard the closing action of the valve upon deenergizing the motor circuit in view of the fact that the blower will coast for some time after its motor circuit is opened, and this is apt to result in blowing out a low burning or minimum flame which would become quite low upon shutting off the gas valve 62 and supplied only through valve 66.

One means for retarding the gas shut off by the valve 62, as shown in Fig. 8, composes an air dash pot cylinder 90 communicating with the valve housing, in which cylinder a hollow piston 91 is contained. Extending down from the valve member 85 into the hollow piston is a stem 93 which, at its lower end, has ball valve member 94 fixed thereto and this is adapted on closing movement of the valve member, to seat over a port 95 in the base of the hollow piston. When the valve member lifts, the ball uncovers the port 95 and also acts as a means for drawing the piston upwardly in the cylinder. Ports 97 in the top wall of the hollow piston then permit ready flow of gas to the under side of the piston, however, with a closing action of the valve member 85, the movement is retarded due to the covering of the gas escape port 95 of the piston by the ball valve.

It will be understood, therefore, that when the thermostat operates to open the motor circuit and deenergize the valve 62, the fan blower coasts to a stop and the closing action of valve 62 is so retarded that some gas is admitted to the burner through valve 62 as long as required to insure against possible blow-out of the flame, and to allow the burner to maintain low flame at atmospheric pressure.

When the blower is not in operation, and no gas is being furnished through the valve 62, gas for low flame burning is furnished to the burner through the pipe connection 65 and solenoid valve 66; it being understood that solenoid valve 66 is open so long as current is supplied through the relay switch 72 to energize the solenoid. A regulating valve 98 is interposed on pipe 65 to control rate of flow of gas for low flame burning.

In installations, spaces or ovens that are not equipped for admittance of secondary air, it is intended to apply the burner construction shown in Fig. 9. In this arrangement I employ a burner tube which, for example, might be like that of Fig. 3. With this tube there is associated an air supply manifold 100. The manifold 100 is supported upon a channel member 37y that is fixed thereto as the channel 27 is fixed to tube 1, and is co-extensive therewith, and air ports 101 are drilled through the base of channel 37y and into the manifold 100 to supply secondary air to the corrugations of plate 35 for supplementing the full mixture from pipe 1. The manifold 100 is supplied with air by a connection 105 with the blower manifold 52.

The automatic control feature of this system shown in Fig. 9 is similar to that of Fig. 6, but eliminates the solenoid valve 66 from pipe connections 65 and places there a hand adjusted valve 66x and a solenoid valve 61x is located in the supply pipe 60 to shut off gas flowing to the system should the pilot flame go out.

In Figs. 7 and 12 I have illustrated the present invention in a dual burner assembly in which two parallel burner tubes are supplied with gas and forced air supply from sources common to both. However, single or multiple burners might be so employed without departing from the spirit of the invention.

In Figs. 11 and 12, the installation shows the baking oven 110 containing the burner tubes in the lower part thereof and below a shelf supporting reel 111. The thermostat 69 and switch 72 are supported from a wall of the oven. Both burner tubes are served by the same pilot burner 68.

With burners so constructed and installed, low burning flame may be used with air at atmospheric pressure, or by use of the blower, high flame is provided. The automatic features of control make possible the safe use and insure against blow out or lift of the flame.

Having thus described my invention, what I claim as new therein and desire to secure by Letters Patent is:

1. A gas burner comprising an elongated burner tube, closed at one end and adapted to be supplied through its other end with a gaseous fuel mixture, under pressure; a closed distributing duct formed along the top side of the tube and there being a succession of ports opening from the tube into the duct at intervals therealong to supply fuel thereinto; said duct having a horizontal top wall and there being a row of closely placed fuel discharge ports from the duct centrally of said wall and throughout its length and a cover plate overlying the tube and ports therein and defining a succession of laterally opening fuel channels that are supplied with fuel from said ports.

2. A gas burner comprising an elongated burner tube, closed at one end and adapted to be supplied at its other end with a gaseous fuel mixture under pressure; said tube having a fuel distributing duct formed along the top side

thereof and a succession of ports opening from the tube into the duct throughout its length; said duct having a horizontal top wall and there being a central, longitudinal fuel distribution channel formed in the top surface of said wall, and there being ports opening from the duct into said channel at spaced intervals therealong, a cover plate overlying the said top wall of the duct in spaced relationship thereto, and means interposed between the plate and top wall defining a succession of laterally opening fuel channels communicating at their inner ends with said wall channel.

3. A gas burner comprising an elongated burner tube, closed at one end and adapted to be supplied at its other end with a gaseous fuel mixture under pressure; said tube having a fuel distributing duct formed along the top side thereof and a succession of ports opening from the tube into the duct throughout its length; said duct having a horizontal top wall and there being a central, longitudinal fuel distribution channel formed in the top surface of said wall, and there being ports opening from the duct into said channel at spaced intervals therealong, a transversely corrugated strip of sheet material disposed flatly on said horizontal wall having all those channels between corrugations at its under side in communication with the wall channel and open at their outer ends to the opposite sides of the burner tube, and means securing said plate in place on the burner tube.

4. A gas burner comprising an elongated burner tube, closed at one end and adapted to be supplied at its other end with a gaseous fuel mixture under pressure; said tube having a fuel distributing duct formed along the top side thereof and a succession of ports opening from the tube into the duct throughout its length; said duct having a horizontal top wall and there being a central, longitudinal fuel distribution channel formed in the top surface of said wall, and there being ports opening from the duct into said channel at spaced intervals therealong, a cover plate overlying the said top wall of the duct in spaced relationship thereto and a transversely corrugated sheet metal plate interposed between the top wall of the duct and the cover plate providing laterally opening fuel discharge channels along opposite sides of the burner tube.

5. A gas burner comprising an elongated burner tube, an overlying gas distribution tube supplying fuel to a succession of flame jets therealong and there being openings from the burner tube into the said distribution tube; said burner tube having an open end, a valve cap adjustably applied to said open end, to control admittance of atmospheric air to the tube, a gas supply means extended into the burner tube near its open end and having a discharge orifice therein directed toward the opposite end of the tube, blower means for supplying primary air under pressure to the burner and having communication with the burner tube at its open end; said valve plate being adjustable to control the intake of atmospheric air to the burner when the blower is not in operation, and adjustable to regulate the escape of excess primary air when the blower means is in operation.

6. A gas burner as recited in claim 1 having a gas supply means that is adjustable to admit gas to the burner in different amounts for a low or for a high burning flame, and having an air inlet port for admission of atmospheric air for low burning flame, and means for increasing the

9

pressure of air immediately about said inlet port to supply additional air for high flame burning.

7. A gas burner as recited in claim 1 having gas supply means and having an air inlet for admittance of air for low burning flame, means for increasing air pressure immediately about the air inlet port, means for supplying additional gas for high burning flame and a control means common to both.
